UNITED STATES PATENT OFFICE.

CHARLES J. BATES, JR., OF ENGLEWOOD, NEW JERSEY, ASSIGNOR TO THE MOSLER
SAFE COMPANY, OF HAMILTON, OHIO, A CORPORATION OF NEW YORK.

LOCK.

Application filed June 24, 1925. Serial No. 39,178.

This invention relates to locks, and more particularly relates to locks comprising tumblers and a spindle for operating the tumblers, and the principal object of my invention is to provide a combination lock, suitable for use on doors of safes, safe cabinets and the like, which cannot be dislodged either by means of tools or explosives.

Other objects of my invention will be in part obvious and in part pointed out hereinafter.

In accordance with my invention, I protect or shield the means whereby the lock case is retained on the wall with drill proof material so located that the case and retaining means cannot be reached by a drill without first drilling through the drill proof protection. I provide an open passage through the case and tumblers which foils attempts to destroy the lock by explosives, by conducting the explosive quickly away from the case and permitting such free expansion of any detonated explosive as to render the effect harmless. I also mount the case on the inner surface of a drill proof plate which has a spindle passage diametrically smaller than the spindle passages through the case and tumblers, and in this way render the case and tumblers inaccessible to an instrument inserted through the spindle passage in the wall. I also so connect the spindle with the tumblers that it is freely movable axially with respect thereto so that the case or tumblers cannot be dislodged by driving the spindle inwardly.

In order that a clearer understanding of my invention may be had, attention is hereby directed to the accompanying drawings, forming a part of this application, and illustrating one possible embodiment of my invention. Referring to the drawing, the figure is a sectional view of a lock embodying my invention mounted upon a double wall construction.

Referring to the drawings, the safe wall on which the lock is mounted comprises an outer plate 1 and an inner drill proof plate 2 spaced from the outer plate. Extending through the outer plate and to the inner plate is a spindle tube 3, preferably of drill proof material. The outer end of tube 3 is threaded to receive the stationary dial plate 4 and lock nut 5. Lock case 6 is secured to the inner face of plate 2 by means of screws 6 which extend through perfora-

tions in plate 2 and engage in threaded perforations in a washer 7 which is in threaded engagement with the inner end of spindle tube 3, as at 8.

About the spindle tube and directly over washer 7 is another washer or plate 9 of drill proof material which prevents access to the washer 7 or screws 6 by a drill or other instrument inserted through outer wall 1, and in the event of removal of the spindle tube. Nor may this washer 9 be penetrated by means of the drill to give access to these members. Thus the lock is secure against burglarious attack at such points. As a modification, the drill proof washer 9 may be omitted and either or both the washer 7 and screws 6 may be made of drill proof material, but this would necessitate the tapping of drill proof material for the screws and thus would increase the cost of the construction. Member 9 may or may not be threaded to tube 3, as desired.

Within the case 6 are regular tumblers 10 and a drive tumbler 11. The spindle hole through the tube 3 and the aligning hole 12 in the plate 2 are of smaller diameter than the holes in the tumblers 10 and 11, and in the arbor 13. For this reason it is practically impossible to engage the case or tumblers with a drill, punch or other instrument inserted through the holes in the walls 1 and 2, should the spindle and its tube be removed. Thus the lock is secure against this manner of attack.

The spindle 14 is squared at a point 15 and is free to slide inwardly through the correspondingly squared hole in the driver 11. The square part of the spindle is larger than the spindle hole 12 in drill proof plate 2. The spindle may be attached and locked to a knob 16 in any suitable manner, for instance, by being threaded into the knob and locked relatively thereto by a key 17 which is held in place by a name plate 18 having a threaded lug 19 screwed into a threaded recess in knob 16. The movable dial plate 20 is secured to the knob.

The construction is such that should the knob 16 and plate 20 be removed in any explosives, since any explosive poured into wards through the spindle passages in the case 6 and tumblers 10 and 11, and through the hole 21 in the case cover 22. As the hole in drill proof plate 2 is smaller than the opening in any part of the lock behind

this plate, it is impossible to dislodge the case or tumblers by operating an instrument from the outside of the safe. As before described, it is also impossible to dislodge or to destroy the lock case mounting by working on the outside of plate 2. A lock constructed and mounted in the manner described defies all efforts to dislodge or destroy or demount the same, so that the safe may not be opened in consequence of such attack.

The above construction also frustrates attempts to destroy the lock by means of explosives, since any explosive poured into the spindle passages will flow right through the same, and if any explosion should occur there is such freedom for expansion of the gases that there will be no destructive consequences.

As many changes can be made in the above construction and as many apparently widely different embodiments of this invention could be made without departing from the scope thereof, it is intended that all matter contained in the above description or shown in the accompanying drawings be interpreted as illustrative and not in a limiting sense.

What I claim is:—

1. The combination with a wall comprising an outer plate and an inner plate spaced therefrom, of a spindle tube extending between said plates, a lock case on the inner surface of the inner plate, a member at the opposite surface of the inner plate and engaging the spindle tube, screws extending through said inner plate and engaging said case and member, securing the case to the plate, and a drill proof plate disposed over said member preventing access to said member and to said screws, substantially as described.

2. The combination with a wall having an elongated spindle passage therethrough, a lock case mounted on the inner surface of said wall, tumblers in said case, a spindle mounted in said passage and detachably connected with said tumblers to actuate the same, and a spindle passage through said case and tumblers in alignment with and diametrically larger than the spindle passage through the wall, whereby the spindle may be moved inwardly through said passages without dislodging the case and tumblers, and whereby said case and tumblers are rendered inaccessible to an instrument inserted through the spindle passage in the wall.

3. The combination with a wall having an elongated spindle passage therethrough, a lock case mounted on the inner surface of said wall, tumblers in said case, a spindle mounted in said passage and detachably connected with said tumblers to actuate the

same, and a spindle passage through said case and tumblers in alignment with and diametrically larger than the spindle passage through the wall, whereby the spindle may be moved inwardly through said passages without dislodging the case and tumblers, and whereby said case and tumblers are rendered inaccessible to an instrument inserted through the spindle passage in the wall, one of said tumblers being a drive tumbler and said spindle having a portion diametrically larger than said wall passage engaging in a perforation of corresponding size in said drive tumbler for simultaneous rotative movement with said tumbler and for free axial movement relative thereto.

4. The combination with a wall comprising an outer plate and an inner plate spaced therefrom, of a spindle tube extending between said plates, a lock case on the inner surface of the inner plate, a member at the opposite surface of the inner plate and engaging the spindle tube, screws extending through said inner plate and engaging said case and member, securing the case to the plate, and a drill proof plate disposed over said member preventing access to said member and to said screws, tumblers in said case, said inner plate having a spindle passage, and the case and tumblers having spindle passages diametrically larger than the passage in said inner plate, whereby said case and tumblers are rendered inaccessible to an instrument inserted from the outside of said wall.

5. The combination with a wall comprising an outer plate and an inner plate spaced therefrom, of a spindle tube extending between said plates, a lock case on the inner surface of the inner plate, a member at the opposite surface of the inner plate and engaging the spindle tube, screws extending through said inner plate and engaging said case and member, securing the case to the plate, and a drill proof plate disposed over said member preventing access to said member and to said screws, tumblers in said case, said inner plate having a spindle passage, and the case and tumblers having spindle passages diametrically larger than the passage in said inner plate, whereby said case and tumblers are rendered inaccessible to an instrument inserted from the outside of said wall, one of said tumblers being a drive tumbler and said spindle having a portion diametrically larger than said wall passage engaging in a perforation of corresponding size in said drive tumbler for simultaneous rotative movement with said tumbler and for free axial movement relative thereto.

This specification signed this 18th day of June, 1925.

CHARLES J. BATES, JR.

Certificate of Correction.

Patent No. 1,614,272, granted January 11, 1927, to

CHARLES J. BATES, JR.

It is hereby certified that error appears in the printed specification of the above-mentioned patent requiring correction as follows: Page 1, strike out line 105 and insert instead *way, the spindle is free to be pushed in*; page 2, line 46, claim 2, for the word "is" read *in*; and that the said Letters Patent should be read with this correction therein that the same may conform to the record of the case in the Patent Office.

Signed and sealed this 1st day of March, A. D. 1927.
